[57] CLAIM

The ornamental design for an electrical receptacle shield, as shown and described.

DESCRIPTION

FIG. 1 is a perspective view of the electrical receptacle shield showing my new design;

FIG. 2 is a front elevational view thereof;

FIG. 3 is a rear elevational view thereof;

FIG. 4 is a right side elevational view thereof, the left side elevational view being a mirror image of the view shown in this FIG.; and,

FIG. 5 is a top plan view thereof, the bottom plan view being a mirror image of the view shown in this FIG.
